ATTORNEYS

UNITED STATES PATENT OFFICE.

THOMAS McDONOUGH, OF MONTCLAIR, NEW JERSEY.

DESIGN FOR A HOE.

SPECIFICATION forming part of Design No. 20,188, dated October 7, 1890.

Application filed August 27, 1890. Serial No. 363,224. Term of patent 14 years.

To all whom it may concern:

Be it known that I, THOMAS McDONOUGH, of Montclair, in the county of Essex and State of New Jersey, have invented a new and Improved Design for Hoes, of which the following is a full, clear, and exact description.

The leading feature of my design consists in the configuration of the blade, which has a bell-like contour in its sides.

Reference is to be had to the accompanying drawing, forming a part of this specification, in which the figure represents in perspective the improved hoe.

A indicates the blade, and B the tang thereof.

The contour of the blade A is that of a bell-

like figure, the defining-lines of which at the sides diverge outwardly toward the bottom, as at $a a$, joining the bottom straight defining-line a' at an acute angle, as shown. The upper edge of the blade is curved inwardly toward the tang B, as at $c c$, the said inward curves at the top being of the same radius as the outer curves $a a$ at the bottom. 20

I claim—

The design for a hoe herein shown and described. 25

THOMAS McDONOUGH.
